UNITED STATES PATENT OFFICE.

EARNEST G. NUFFER, OF PHILADELPHIA, PENNSYLVANIA, ASSIGNOR TO GEORGE BROOKS & SON, OF SAME PLACE.

DESIGN FOR A TAPESTRY BORDER.

SPECIFICATION forming part of Design No. 15,097, dated June 24, 1884.

Application filed May 5, 1884. Term of patent 3½ years.

To all whom it may concern:

Be it known that I, EARNEST GARIBALDI NUFFER, a subject of the Emperor of Germany, residing at Philadelphia, in the county of Philadelphia and State of Pennsylvania, have invented and produced a new and original Design for a Border in Woven Tapestry Fabrics, in such shades as may be desired; and I do hereby declare that the photographic print accompanying this specification conveys to any one skilled in the art a clear understanding of the same, and is sufficient to enable such persons to use my invention.

What I claim as my invention, and desire to secure by Letters Patent, is—

The design for a border in tapestry fabrics, as shown in the photographic print accompanying this specification. 15

EARNEST G. NUFFER.
